HOOK

John G. Sprung, Chicago, Ill., assignor to Gordon T. Brummel, Chicago, Ill.

Application January 31, 1950, Serial No. 7,582

Term of patent 14 years

(Cl. D54—11)

To all whom it may concern:

Be it known that I, John G. Sprung, a citizen of the United States, residing at Chicago, in the county of Cook and State of Illinois, have invented a new, original, and ornamental Design for a Hook, of which the following is a specification; reference being had to the accompanying drawing, forming a part hereof.

In the drawing:

Fig. 1 is a perspective view of the hook showing my new design;

Fig. 2 is a plan view of the hook;

Fig. 3 is a side elevation of the hook;

Fig. 4 is an elevation of one end of the hook; and

Fig. 5 is an elevation of the opposite end of the hook.

I claim:

The ornamental design for a hook, substantially as shown and described.

JOHN G. SPRUNG.
